CARBURETOR

Henry P. Vaughan, Detroit, Mich., assignor to
Detroit Lubricator Company, Detroit, Mich., a
corporation of Michigan

Application September 17, 1930, Serial No. 482,411

7 Claims. (Cl. 261—51)

My invention relates to new and useful improvements in carburetors for internal combustion engines.

In carburetor operation, fuel supplied to the air stream from a jet of fixed orifice provides a mixture which when of proper proportions for normal running conditions, is too lean or poor in fuel to obtain maximum engine speed or full load engine operation. It is therefore an object of my invention to provide a carburetor in which the ratio of fuel to air is increased for full load and high speed engine operation.

Another object is to control the additional supply of fuel in accordance with the position of the mixture flow control means or throttle so as to bring in the additional fuel supply at the proper point in the engine operation.

The invention consists in the improved construction and combination of parts, to be more fully described hereinafter, and the novelty of which will be particularly pointed out and distinctly claimed.

In the accompanying drawing to be taken as a part of this specification, I have fully and clearly illustrated a carburetor embodying my invention, and in which drawing—

Figure 1 is a view in vertical central section of so much of a carburetor as is necessary to show my invention;

Fig. 2 is a detail sectional view of a modification of the carburetor of Fig. 1, and

Fig. 3 is a detail sectional view of another modification.

Referring to the drawing by characters of reference, 1 designates generally a carburetor casting comprising a base or bottom member 2 having a constant level fuel reservoir or float chamber 3 and a main air inlet 4, which are separated by a partition or wall member 5 having a fuel well or reservoir 6 therein. Seated on the member 2 is a hollow throttle body member 7 having a lateral extension or cover member 8 which overlies and closes the reservoirs 3 and 6. Secured within the hollow member 7 and depending therefrom into the air inlet 4, is a Venturi tube 9 forming the lower end of the carburetor mixing chamber 10. Extending from the wall 5 into the air inlet 4 is a boss 11 having a vertical bore 12 therethrough substantially concentric with the tube 9 and closed at its bottom end by a plug 13. Between the bore 12 and reservoir 3 is a substantially horizontal conduit or passageway 14 which is below the normal liquid fuel level in reservoir 3, designated by line L—L. In the boss 11 is a conduit or passageway 15 con-

nected the bore 12 and the fuel well 6 at its lower end. In the bore 12 between passageways 14 and 15 is a plug 16 carrying a tube comprising a main nozzle 17 which extends upward spaced from the wall of the bore 12 and which terminates in the throat of the tube 9 above the normal liquid level. Through the plug 16 is a calibrated port 18 forming the main fuel jet, and which feeds the nozzle 17. Surrounding the nozzle 17 and terminating in the Venturi throat is a tube or sleeve comprising a supplemental nozzle 19 providing an annular discharge passage, and which is threaded at its lower end into the top end of the bore 12. Adjacent the base of the sleeve or nozzle 19 are air inlet apertures or bleeds 20 which supply air at substantially atmospheric pressure to the interior of nozzle 19 below the normal liquid fuel level. At the lower end of the well 6 above the passageway 15 is a plug or partition member 21 having a valve port 22 therethrough and serving as the bottom wall of the well 6. Beneath the member 21 is a recess or valve chamber 23 from which the passageway 15 opens. In the chamber 23 is a valve member 24 which seats upwardly against the plug 21 to close port 22 and which is normally urged toward closed position by a coil spring or the like 25 positioned between the member 24 and the bottom wall of chamber 23. In the wall 5 below the normal liquid level, is an aperture 26 which opens from reservoir 3 into well 6. In the aperture 26 is a plug 27 having a calibrated bore 28 for controlling fuel flow from reservoir 3 to well 6. Atmospheric pressure is maintained over the fuel in reservoir 3 by an aperture 29 in cover member 8 and in well 6 by a port 30 in wall 5 opening into reservoir 3 above the liquid level therein. Through the cover member 8 in line with the valve port 22 is a guide aperture 31 through which extends a push-rod or valve operating member 32 which is of reduced cross-section at its lower end, as at 33. The end 33 which is of less diameter than port 22, extends into port 22 and into engagement with valve member 24 and provides an annular fuel flow space therearound through port 22. Journaled in the member 7 and projecting outward through the walls thereof above tube 9, is a throttle shaft 34 rotatable by any suitable means and having fixed thereon a throttle valve or plate 35 to control the discharge from the mixing chamber 10. One of the projecting ends of shaft 34 extends substantially directly over the guideway 31 and has fixed thereon a cam or the like 36 for engage-

ment with the end of rod 32 to depress the rod upon predetermined opening movement of the throttle valve. The cam 36 is provided with a set screw 37 so that the cam may be adjusted about the shaft 34 to regulate the point in the throttle opening movement at which rod 32 will be actuated to open valve 24.

In Figs. 2 and 3 are shown modifications of the application of the air inlet 20 to the auxiliary fuel nozzle 19. In Fig. 2 an air inlet passage or bleed 38 is provided in boss 11 in line with passageway 15 and opening from bore 12 to the air inlet 4. In Fig. 3, an air inlet passage or bleed 39 opens from passageway 15 intermediate its ends and upwardly through wall 5 to the atmosphere. Each of the passages 38 and 39 is preferably provided with a plug 40 having a calibrated bore 41 to regulate the inlet of air.

The operation of my carburetor is as follows: During normal operation of the carburetor corresponding to level road car speeds, the cam 36 will not have been rotated sufficiently to depress rod 32 and open valve 24. Thus, the fuel will only be supplied to the mixing chamber 10 through the main jet 18 and the nozzle 17. However, when the throttle 35 is opened to provide for high speeds or power demands, the cam 36 will be rotated far enough to depress rod 32 and open valve 24 against the force of spring 25. Fuel which is in the well 6 will now flow by gravity as well as by difference of air pressures in the legs 6 and 19 to the bleeds 20 where the air entering nozzle 19 from inlet 4 will emulsify the fuel before discharge thereof into the mixing chamber. When the well 6 has been emptied, fuel entering from the port 28 and air from port 30 will form an emulsion which will continue to flow to the nozzle 19 to enrich the mixture in the chamber 10 as long as the valve 24 is held open. It is to be noted that when the throttle is first moved far enough open to open valve 24, that the supplemental discharge of fuel will be greater in quantity per unit of time than will occur after the well 6 has been emptied, which operation I have found to be desirable.

The operation of the modifications shown in Figs. 2 and 3 will be apparent from the foregoing description of the operation of the carburetor shown in Fig. 1.

What I claim and desire to secure by Letters Patent of the United States is:—

1. A carburetor of the character described, comprising a casing having a mixing chamber, a throttle valve to control flow from said chamber, an air inlet to said chamber, a fuel nozzle discharge tube positioned in said inlet and discharging upwardly into said chamber, a second nozzle tube positioned in said air inlet and discharging into said chamber, a fuel well, means to supply air to said well, a valve chamber beneath said well and substantially concentric therewith, a partition between said well and valve chamber and having a valve port, a passageway connecting said valve chamber and said second-named nozzle tube, a valve in said valve chamber cooperable with said port, means to supply fuel to said well, and throttle operated means to open said last-named valve.

2. A carburetor of the character described, comprising a casing having a mixing chamber with a main air inlet, a main fuel nozzle discharging into said mixing chamber, a fuel supply conduit opening directly into said main nozzle, a normally inactive supplemental fuel nozzle

operable to discharge fuel directly into said mixing chamber, said main air inlet being common to said main and said supplemental nozzles, an atmospheric fuel well, a fuel supply conduit leading from said well to said supplemental nozzle and being the sole means for supplying fuel to said supplemental nozzle, a valve in said conduit, an air inlet operable to supply air to said supplemental nozzle below the normal fuel level and on the outlet side of said valve, said valve normally cutting off the supply of fuel to said supplemental nozzle whereby said supplemental nozzle discharges air alone into said mixing chamber, a throttle valve having a shaft, and means operable by said shaft to open said supplemental fuel valve to supply fuel to said supplemental nozzle whereby said supplemental nozzle will discharge an emulsion of air from said second-named air inlet and fuel from said conduit into said mixing chamber.

3. A carburetor of the character described, comprising a casing having a mixing chamber with a main air inlet, a main fuel nozzle discharging into said mixing chamber, a fuel reservoir means to supply fuel directly from said reservoir to said main nozzle, a normally inactive supplemental fuel nozzle operable to discharge fuel directly into said mixing chamber, a fuel supply conduit leading to and being the sole means for supplying fuel to said supplemental nozzle, an atmospheric fuel well supplying said conduit, a plug having a calibrated port connecting said reservoir and said well, a valve in said conduit, an air inlet opening from said main air inlet and operable to supply air to said supplemental nozzle below the normal fuel level and on the outlet side of said valve, said valve normally cutting off the supply of fuel to said supplemental nozzle whereby said supplemental nozzle discharges air alone into said mixing chamber, a throttle valve having a shaft, and means operable by said shaft to open said valve to supply fuel to said supplemental nozzle whereby said supplemental nozzle will discharge an emulsion of air from said second-named air inlet and fuel from said conduit into said mixing chamber.

4. A carburetor of the character described, comprising a casing having a mixing chamber with a main air inlet, a tubular nozzle extending into said mixing chamber, a fuel reservoir, a conduit directly connecting said reservoir and said nozzle, a normally inactive supplemental tubular nozzle surrounding said first-named nozzle, a fuel well extending above the normal fuel level and open to atmosphere, means to supply fuel from said reservoir to said well, a conduit connecting said well and said supplemental nozzle and being the sole means for supplying fuel to said supplemental nozzle, a valve normally closing said second-named conduit whereby to prevent discharge of fuel to form said supplemental nozzle, and means continuously supplying air through said supplemental nozzle into said mixing chamber whereby upon opening said valve said supplemental nozzle will discharge an emulsion of air and fuel into said mixing chamber.

5. A carburetor of the character described, comprising a casing having a hollow throttle body member and a base member supporting said throttle body member, said base member having an air inlet and a fuel reservoir, a partition separating said inlet and said reservoir, a fuel well in said partition, a fuel nozzle in said air inlet

and discharging into said throttle body member, a conduit connecting said reservoir and said nozzle, said throttle body member having a lateral extension closing the top of said well and said reservoir, means to supply air to said reservoir above the normal liquid level, means to supply air from said reservoir to said well above the normal liquid level in said well, a supplemental fuel nozzle discharging into said throttle body member, a conduit from said well to said supplemental nozzle, and a valve controlling communication between said well and said second-named conduit.

6. A carburetor of the character described, comprising a casing having a hollow throttle body member and a base member supporting said throttle body member, said base member having an air inlet and a fuel reservoir, a partition separating said inlet and said reservoir, a fuel well in said partition, a fuel nozzle in said air inlet and discharging into said throttle body member, a conduit connecting said reservoir and said nozzle, said throttle body member having a lateral extension closing the top of said well and said reservoir, means to supply air to said reservoir above the normal liquid level, means to supply air from said reservoir to said well above the normal liquid level in said well, a supplemental fuel nozzle discharging into said

throttle body member, a conduit opening at one end through the bottom wall of said well and connected at its other end to said supplemental nozzle, a valve controlling communication between said well and said second-named conduit, a reciprocable rod extending through and guided in said extension, said rod engaging said valve, and means to move said rod to open said valve.

7. A carburetor of the character described, comprising a casing having a hollow throttle body member and a base member supporting said throttle body member, said base member having an air inlet and a fuel reservoir, a partition separating said inlet and said reservoir, a fuel well in said partition, a fuel nozzle in said air inlet and discharging into said throttle body member, a conduit connecting said reservoir and said nozzle, cover means for said well and for said reservoir, means to supply air to said reservoir above the normal liquid level, means to supply air from said reservoir to said well above the normal liquid level in said well, a supplemental fuel nozzle discharging into said throttle body member, a conduit from said well to said supplemental nozzle, and a valve controlling communication between said well and said second-named conduit.

HENRY P. VAUGHAN.
